UNITED STATES PATENT OFFICE.

MAX BECK AND CHARLES SCHNEIDT, OF PHILADELPHIA, PENNSYLVANIA.

IMPROVEMENT IN BOOT-BRUSHING APPARATUS.

Specification forming part of Letters Patent No. **141,196**, dated July 29, 1873; application filed April 30, 1873.

To all whom it may concern:

Be it known that we, MAX BECK and CHAS. SCHNEIDT, both of Philadelphia, Pennsylvania, have invented an Improvement in Boot-Brushing Apparatus, of which the following is a specification:

The object of our invention is to enable those who are about to enter a house to readily and effectually clean their boots or shoes by means of a fixed apparatus, consisting of a series of brushes, *a a*, for removing dirt from the soles, side brushes *b b* for cleaning the edges of the soles, and an arched brush, *d*, for the toes of the boots or shoes, the whole being secured to a frame-work, *A*, containing a drawer, *B*, for receiving the dirt, and having in front a scraper, *e*, all as shown in the vertical section, Figure 1, and in the transverse section, Fig. 2, of the accompanying drawing.

The frame-work consists of the two side pieces, *A A*, connected together in front by the scraper *e*, at the rear by the arched brush *d*, and at intermediate points by the transverse brushes *a a*, the whole being arranged for attachment to the floor in a vestibule, or at any other suitable point near the door of a dwelling. The brushes *a a* are arranged at such a distance apart that the dirt which they are the means of removing from the sole of a boot or shoe, as well as the dirt removed from the

edges of the sole by the side brushes *b b*, shall fall into the drawer *B*, which also receives such of the dirt as may be removed from the sole by drawing it across the edge of the scraper *e*, and from the toes by rubbing it against the arched brush *d*, all the brushes being so arranged that, by a proper movement of the foot, they shall be the medium of quickly and effectually cleaning a boot or shoe.

If desired, the apparatus may be furnished with a base, *X*, indicated by dotted lines in Fig. 1, for convenience of attachment to a stone or marble floor.

We claim as our invention—

1. The combination of the brushes *a a*, the side brushes *b b*, and arched brush *d*, arranged above and at the rear of the brushes *a b*, as set forth.

2. The combination, in a boot-brushing machine, of a series of independent brushes, *a a*, arranged as and for the purpose set forth.

In testimony whereof we have signed our names to this specification in the presence of two subscribing witnesses.

MAX BECK.
CHAS. SCHNEIDT.
